SHEET CONTROLLED ROTARY PRINTING
PRESSClyde W. Johnson, Islington, Mass., assignor, by
mesne assignments, to A. B. Dick Company,
Niles, Ill., a corporation of Illinois

Application July 13, 1948, Serial No. 38,465

5 Claims. (Cl. 101—233)

1

This invention relates to printing machines and more particularly to printing machines wherein an ink impression is transposed from a lithographic plate to a printing cylinder and then further transposed from the printing cylinder to a sheet of paper.

In lithographic printing the impression or image to be reproduced is placed on a lithographic plate using a greasy ink or crayon. The plate is then chemically treated to fix the impression if such is necessary depending upon the type of ink or crayon used in applying the impression. Printing from this plate is carried out by first moistening it and then applying printing ink to it. During the moistening phase the liquid does not adhere to the ink or crayon image, and during the inking phase, the printing ink adheres only to the original ink or crayon impression. The plate is then ready for printing and is impressed upon a printing blanket which retains the ink impression and finally serves to print the impression upon a sheet of paper. This process is analogous to true printing as distinguished from duplicating, multigraphing, mimeographing, etc., because printing ink is applied to the face of the plate, and does not pass through the plate, or come out of the plate itself as in the other processes. Furthermore, this process does not require a special type of paper as the others do.

Conventional printing machines heretofore employed for this type of printing have numerous inconveniences. First, they are bulky. Due to the pressures involved and the centrifugal forces developed when printing at high speed, heavy metal cylinders have been used universally. These cylinders and the heavy metal frames used to support them have rendered the conventional machines inordinately heavy. Secondly, the conventional machine of this type takes up considerable space. Usually the paper sheets go in the front and shoot out at the back into a pan. This necessitates placing the machine in the middle of the working space, or at least, lengthwise along a wall, and it means that the operator must walk around the machine to obtain test samples. A third undesirable aspect of the conventional machine is the lack of handy control mechanism governing the relative amounts of water (or liquid grease repellent) and ink being applied to the rolls. These relative amounts are usually fixed by permanent design features or can be changed only by laborious adjustment. A fourth disadvantage lies in the use of mechanical trips for the purpose of preventing the press cylinder from contacting the printing cylinder without a sheet

2

of paper between them. These mechanical trips are not well adapted to respond to extremely fine paper, they involve numerous moving parts, they are noisy and hard to keep in repair. Still another inconvenient aspect of the conventional machine is the mechanism used in attaching the lithographic plate to the plate cylinder. Unlike mimeograph procedure the plate in a lithographic machine must be secured at both ends and drawn tight. In the past this has been accomplished by placing the lithographic plate on hooks and then tightening up by means of screws.

An object of the present invention is to provide a lithographic printing machine which is light, which can be operated in the corner of a room without taking up space, and which can be operated by a person standing in one position. Another object of the invention is to provide convenient ink and moisture controls within reach of the operator in the said position, which controls will allow both quantity adjustment and complete disconnection of either the water or ink from the lithographic plate.

25 A further object is to provide a simple mechanism for securing the lithographic plate tightly to the plate cylinder without the necessity for screw adjustments. Still another object of my invention is to provide an extremely sensitive 30 electrically operated trip to detect the presence of paper ready to enter between the printing cylinders. Another object is to provide a control mechanism whereby the pressure of the printing blanket against the lithographic plate 35 can be conveniently regulated or the printing blanket completely disengaged from the lithographic plate.

For purposes of illustration the novel features 40 of this invention are herein shown as embodied in a lithographic printing machine basically similar to that disclosed in my copending application Serial No. 755,065, now U. S. Patent No. 2,590,179. A majority of its cylinders and its side plates are made of aluminum greatly reducing the overall 45 weight of the machine. The ink, moisture and printing blanket cylinders are mounted by use of roller bearings to rotate on eccentric shafts which can be adjusted by hand to disengage their respective cylinders from the lithographic plate 50 cylinder or to regulate their pressures against the lithographic plate cylinder. On the lithographic plate cylinder, I employ a novel clamping device which secures the plate and holds it tightly to the cylinder and which may be operated without 55 laborious adjustment. I provide an extremely

sensitive micro-switch located in the path of the paper sheet as it approaches the rolls and through its operation, I prevent the pressure cylinder from coming into contact with the printing blanket cylinder in the absence of a sheet of paper between them. In order to return each printed sheet to the front of the machine, a set of gripper jaws is placed behind the bite between the two cylinders and arranged to operate in timed relation with the said cylinders. These jaws engage the leading edge of the sheet and guide it rearwardly for a short distance after which the sheet slides onto a series of conveyor belts which return it to a receptacle at the front of the machine.

An additional feature of my invention is a set of cooperating rolls which engage the sheet prior to its entry into the printing mechanism. These rolls operate in timed relation with the gripper jaws and cause the sheet to pass between the blanket cylinder and pressure cylinder, and enter the gripper jaws just before the instant when the blanket cylinder and pressure cylinder come into contact with each other.

Still another feature of my invention consists in a prong of novel shape for stripping the sheet from the gripper jaws. It is provided with a protruding belly shaped surface which has the effect of preventing the successive sheets from diving into the forward conveyor, and coming out wrongside up.

These and other objects and features of my invention will best be understood and appreciated from the following description of a preferred embodiment thereof, selected for the purpose of illustration and shown in the accompanying drawings in which:

Fig. 1 is a view in perspective of the entire machine as seen from the front right,

Fig. 2 is a view in cross section of the right-hand end of the plate cylinder, shaft and bushings,

Fig. 3 is a view in perspective of the plate cylinder, the blanket cylinder, and the pressure cylinder as seen from the front left with the left side plate broken away,

Fig. 4 is a sectional view in side elevation from the right, through a plane coinciding with the left ends of the cylinders,

Fig. 5 is a sectional view in side elevation from the right showing the paper stops and the pressure cylinder operating micro-switch,

Fig. 6 is a fragmentary view in perspective showing the micro-switch and its working arm,

Fig. 7 is an exploded view in perspective showing in detail the feed control mechanism as seen from the right front,

Fig. 8 is a view in side elevation showing the paper stop arm and upper feed roll,

Fig. 9 is a view in section from the left showing in detail the gripper mechanism which guides the paper rearwardly from between the cylinders,

Fig. 10 is an enlarged view of the gripper jaws showing them at the top of their forward stroke, and

Fig. 11 is a sectional view of the left hand end of the plate cylinder shaft.

Before going into a description in detail of the preferred embodiment of my invention, a brief survey of its principal parts and their operation will best serve the needs of clarity. A lithographic plate or sheet 30 is wrapped around a cylinder 15 mounted between the main frame side plates 10 and 12. Adjacent and parallel to the cylinder 15 is a cylinder 70 upon which a

rubber printing blanket 80 is mounted. These two cylinders are contiguous, are of the same diameter and have intermeshing geared drive as will be explained presently, the point of interest here being that they rotate in unison. Ink and water are applied to the lithographic plate 30 by rolls to be described later, and the plate 30 rotates and deposits an ink impression upon the surface of the printing blanket 80. Below the printing cylinder 70 is a pressure cylinder 90 which is mounted for vertical movement in its journals 91 to enable it both to press a sheet of paper against the blanket cylinder and to withdraw from the blanket cylinder when no paper is in between. In front of these cylinders is a paper feeding device which employs endless belts 100 to carry successive sheets of paper up to the bite between the cylinder 70 and the pressure cylinder 90. When a sheet of paper reaches position, stops 107 operate to release the sheet and the pressure cylinder 90 automatically rises in exact timing with the blanket cylinder 70. Thereupon the sheet passes between the blanket cylinder 70 and the pressure cylinder 90 at which time the ink impression on the printing blanket 80 is transposed onto the sheet of paper. The sheet is guided rearwardly by gripper jaws acting in unison with the blanket cylinder 70, and finally, the sheet is dropped and conveyed to the front again by endless belts 151 (shown only in Fig. 1).

Proceeding now to a detailed description of the preferred embodiment of the invention as herein shown, the illustrated machine consists in a main frame made principally of aluminum with transversely spaced right and left side plates 10 and 12 respectively, which are connected to each other and held in properly spaced relationship by tie rods and other parts which are supported in a suitable base indicated generally at 14.

An aluminum cylinder 15 is mounted horizontally between the side walls 10 and 12 upon a fixed shaft 18. The cylinder 15 is cut away on one side and provided with a recess 31 into which the ends of a flexible lithographic plate 30 fit as will be described presently. The shaft 18 is held in bushings 20 and 21 which are in turn secured to the side walls 10 and 12. The cylinder 15 rotates freely upon the said shaft 18 by means of roller bearings 16 located in hubs 17 at each end of the cylinder 15. In order to allow free rotation of the cylinder 15 but at the same time preventing it from slipping laterally, the shaft 18 is provided with a flange 22 at its left end and a shoulder 23 near its right end. The distances between the flange 22, the shoulder 23, and the bushings 20 and 21 are accurately machined such that when the bushing 20 is drawn up tight against the shoulder 23 by the lock-nuts 19, and when the flange 22 is lodged in the counterbore 24 provided for it in the bushing 21, the distance between the inside walls of the bushings 20 and 21 will be no more than is sufficient to allow free rotation of the cylinder 15.

Inasmuch as the hubs 17 are made of aluminum, two steel caps 25 are placed over the hubs 17 and present a steel face opposing the inside walls of the bushings 20 and 21.

At the base of the hub 17 in the right end of the cylinder 15 a gear 26 concentric with the cylinder 15 is held between an upstanding flange on an annular sleeve 27 and an annular ring 28. The sleeve 27 is secured to the cylinder 15 by machine screws and the annular ring 28 is threaded on its inside to screw onto the inner end of the sleeve 27, and when tightened by use of a spanner

wrench the annular ring 28 holds the gear 26 rigidly against the flange of the sleeve 27. This latter described mechanism allows the cylinder 15 to be given minor rotational adjustment when it is desired to raise or lower the printed impression upon the printed page.

The lithographic plate 30 is secured to the outer surface of the cylinder 15. As herein shown, the lithographic plate 30 comprises a sheet of paper prepared to be receptive of an impression formed by the application thereto of ink or other printing material of greasy character. During the printing process the lithographic plate is maintained in a moist condition and printing ink is applied thereto as will be described in detail presently. The moisture which is applied first does not adhere to the greasy ink impression and conversely when the printing ink is applied it only adheres to the greasy ink impression. Thereafter the ink impression is transferred to the printing blanket 33 and printed upon the paper sheet as will also be described presently.

The mechanism for securing the lithographic plate 30 to the cylinder 15 will now be described. A flat bar 33 is secured to the cylinder 15 by screws and located in the recess 31 within the radius of the said cylinder. A shaft 34 passing through journals in the ends of the plate cylinder 15 is located under the flat bar 33 and parallel to it. The shaft 34 is provided with upstanding lugs 35 which are located to touch the bar 33 when the shaft 34 is rotated. At each end of the shaft 34, helical springs 36 are provided which hold the lugs 35 in restrained relation against the flat bar 33. A thumb lever 37 is provided at the left end of the shaft 34 for the purpose of rotating the said shaft and thereby allowing the lithographic plate 30 to be inserted between the flat bar 33 and the lugs 35. A peep hole 38 is provided in the flat bar 33 for the purpose of observing whether or not the lithographic plate 30 is fully seated.

After insertion under the bar 33, the lithographic plate 30 is wrapped around the cylinder 15 until it meets a second flat bar 40 disposed parallel to the flat bar 33 and which has inwardly extending arms 41 pivotally connected near the core of the cylinder 15. The flat bar 40 is likewise located within the recess 31 and at no time does it project outside of the circumference of the cylinder 15. A shaft 42 similar to the shaft 34 is mounted parallel to the bar 40 and likewise carries lugs shown only at 43 in Fig. 4. The shaft 42 is also provided with springs (not shown) similar to the springs 36 and which rotate the shaft 42 such that the lugs 43 are urged always against the bar 40. Two tension springs 44 are secured at one end to the cylinder 15 at the base of the flat bar 33 and at the other end of the springs to the arms 41 of the bar 40. These latter springs tend to swing the bar 40 towards the bar 33.

At the left end of the shaft 42 a control lever 46 is provided for the purpose of rotating the shaft 42 to disengage the lugs 43 from the bar 40. The control lever 46 is provided with a slanting end and a circular groove set back from the end. Directly facing the slanting end is a steel pin 47 located so that the slanting end of the control lever will engage it. Thus when the flat bar 40 is rocked toward the pin 47 the control lever 46 is raised by the pin 47, the shaft 42 is rotated, the lugs 43 separate from the under surface of the flat bar 40 and the control lever 46 locks with the pin 47 by means of the above mentioned circular groove. In this position the lithographic

plate 30 is inserted between the lugs 43 and the flat bar 40. Thereafter the final clamping step merely involves pulling the bar 40 toward the bar 33. The control lever 46 then disengages from the pin 47 and the lugs 43 snap up against the lithographic plate 30 holding it firmly against the bar 40. Thereupon the springs 44 acting to pull the bar 40 toward the bar 33 pull the lithographic plate tightly around cylinder 15.

10 Above the cylinder 15 is the moisture applying apparatus. It comprises a frame including aluminum side plates 50 and 51 maintained in spaced relationship by suitable tie rods. The side plates 50 and 51 are secured to the upper edge of the side plates 10 and 12 and render the moisture applying apparatus detachable as a complete unit. A tubular flask 52 containing water or other grease repellent liquid is supported horizontally across the top of the frame by braces 53 which are in turn connected to the side plates 50 and 51. The liquid is then fed into a trough (not shown) from which it is picked up by a metal cylinder 54, which has a knurled surface that is wetted by the liquid. The liquid is then transferred to an intermediate spreading cylinder 55 which presents a felt or similar fabric surface, thence to another similar cylinder 56 and finally to the moisture applying or molleton cylinder 57. The cylinder 57 which is at all times parallel to cylinder 15 is mounted for free rotation upon an eccentric shaft 58 by roller bearings (not shown) similar to those used in connection with the cylinder 15 (Fig. 2), and is driven by a gear 60 which is secured to its right end and which intermeshes with the gear 26 of the cylinder 15. The shaft 58 is eccentric by being offset uniformly at each end of the cylinder 57, but it is to be understood that the cylinder 57 rotates uniformly about its own axis. A hand knob 61 is provided at the left hand end of the shaft 58 and when it is used to turn the shaft 58, it operates through the eccentricity of the shaft 58 to bring the cylinder 57 into contact with the lithographic plate 30. By this knob 61 greater or less pressure between the cylinders 15 and 57 can likewise be regulated.

45 The cylinder 56 is disposed parallel to the molleton cylinder 57 and touches it at all times thereby being rotated by the friction between them. In order to account for change of position of the molleton cylinder 57 however, the cylinder 56 is mounted to slide in vertical channels 63. The other cylinders 55 and 54 are likewise contiguous in succession and are mounted in suitable bearings in the side plates 50 and 51.

50 55 The printing ink applying apparatus will not be completely described inasmuch as it comprises conventional spreading rolls and a final applying roll which rotates in unison with the cylinder 15. It is of note however that the ink applying apparatus is mounted upon a frame which is provided with an eccentric shaft of the same shape as the shaft 58. This latter shaft can be rotated to allow either a complete disengaging of the ink applying roll from the cylinder 15, or varying degrees of pressure between the cylinder 15 and the ink applying roll.

55 60 Proceeding now to the printing apparatus, it consists in the cylinder 10 which lies below and parallel to the cylinder 15. The cylinder 10 is recessed on one side at 71. It is mounted by means of roller bearings to rotate freely upon a shaft 72 (see Fig. 4). The shaft 72 is offset at each end of the cylinder 10 rendering it eccentric and by use of a hand lever 73, serves to move the cylinder 10 into contact with the cylinder 15 and

also to regulate the pressure between the two said cylinders. It is to be noted that the cylinder 70, as well as the roll 58, rotate freely upon the shafts which support them, and eccentricity of the shafts becomes effective only when the side controls are turned.

The cylinder 70 is driven by means of a gear 74 which is secured to the end of the cylinder 70 by screws and which intermeshes with the gear 26. Incidentally, although the turning of the eccentric shaft 72 disengages the cylinder 70 from contact with the cylinder 15, it does not totally separate the gear teeth. This is likewise true of the other gears above described which are mounted on eccentric shafts.

In order to allow free rotation of the cylinder 70 but at the same time to prevent it from slipping laterally on the shaft 72, cams 75, which serve an additional purpose to be explained presently, are secured to the shaft 72 by taper pins and are located in such position on the said shaft that their inner walls are exactly far enough apart to allow cylinder 70 to rotate freely but not to slide horizontally. A screw 76 is threaded into the left hand end of the shaft 72 and serves to hold the lever 73 in place upon the squared end of the shaft 72. The right hand end of the shaft 72 then fits freely in a bushing 78 (see Fig. 1 outside), the lateral play of the shaft being taken care of by the cams 75 fitting snugly between the shaft bushings on each end.

A sheet of porous or resilient material conveniently termed a "printing blanket" 80 is secured to the face of the cylinder 70 being hooked within the recess 71 at one of its edges, wrapped around the cylinder face, and hooked again at its other edge within the recess 71 by the hooks 81. On one side of the recess 71, the hooks 81 are mounted on the cylinder 70, but on the other side of the recess 71 they are mounted on a transverse bar 82 which is held in position and drawn toward the center of the cylinder 70 to tighten the blanket 80 by the screws 83 which are conveniently threaded to the core of the cylinder 70.

Directly beneath the blanket cylinder 70, a steel pressure cylinder 90 is mounted parallel to the blanket cylinder 70, in journals 91 which are arranged to slide vertically in guides 92. A compression spring 93 is located under each journal 91 and tends to press the cylinder 90 up against the blanket cylinder 70. The pressure of the springs 93 is adjustably controlled by set screw 94. A flat hardened plate 95 is secured to the top of each journal 91 by screws and cooperating with the cams 75, serves to hold the pressure cylinder 90 away from the blanket cylinder 70. It is to be noted, however, that the cams 75 only engage the plates 95 and depress the pressure cylinder 90 at times when the shaft 72 is rotated by means of the hand lever 73 for the purpose of disengaging the blanket cylinder 70 from the plate cylinder 15. The journals 91 are each provided with a notch in their forward walls for the purpose of holding the cylinder 90 in the lowered position as will be explained presently.

In addition to the cams 75, there is another pair of cams 96 which depress the cylinder 90 against the compression of the springs 93. This latter mentioned pair of cams 96 are mounted on the ends of the cylinder 70 and secured to it by screws. Unlike the cams 75 which force the journals 91 downwardly only when the shaft 72 is turned, the cams 96 engage the pressure cylinder 90 at the rings 98 during each cycle of the blanket cylinder 70. The cams 96 are positioned to de-

press the pressure cylinder 90 during the part of the cycle of the blanket cylinder 90 when the recess 71 passes the pressure cylinder 90.

The pressure cylinder 90 is driven in rotation by a gear 97 which is silver soldered to it and the teeth of which intermesh in the teeth of the gear 74. Although the gears 97 and 74 move sufficiently apart to allow their respective cylinders to separate, this movement is not enough to disengage the gear teeth.

The apparatus for feeding the paper into the machine will now be described. It comprises a series of endless belts 100 mounted on suitable rollers and driven by a belt (not shown) suitably connected to the source of power. The belts 100 approach the machine at a slight angle, approximately 3°, for the purpose of continuously aligning the successive sheets of paper against the guides 101. A conventional friction feeder (not shown), driven by the belts 100 may be used to place successive sheets of paper on the belts 100. Proceeding over the belts 100, the sheet of paper slides between a lower plate 102 and an upper plate 103 which lie one on top of the other and are secured in a horizontal position to the main frame. The plates 102 and 103 are dished to provide space between them for the paper to pass, and spread at their forward edges to provide a funnel shaped entrance for the successive sheets. The upper plate 103 is provided with a series of transversely disposed holes for the purposes of permitting the entrance of air, and also to lighten the assembly. The lower plate 102 extends considerably more towards the rear than does the upper plate 103, the lower plate's rear edge being adjacent to the bite between the pressure cylinder 90 and the blanket cylinder 70. Midway in the lower plate 102 and to the rear of the upper plate 103, a slot 104 is provided to permit a paper feed roll 105 to extend upwardly through the said lower plate 102. Further towards the rear of the lower plate 102, transversely spaced holes 106 are provided to allow stop lugs 107 to pass upwardly through the lower plate 102, and arrest the passage of the paper when such is desired. A retainer plate 108 is secured to the lever plate 102 between the slot 104 and the holes 106 to prevent the paper from accidentally hopping over the stop lugs 107. This function of the retainer plate 108 is aided by notches in its rear edge which correspond to the holes 106 and allow it to extend somewhat around the stop lugs 107 when they are in the raised position. The forward edge of the retainer plate 108 is bent upwardly to aid in guiding the paper between it and the lower plate 102. This can be seen in side elevation in Fig. 5.

The paper feed roll 105 is mounted horizontally in suitable bearings secured to the main frame, and lies parallel to the pressure cylinder 90. The feed roll 105 is provided with a chain drive 110 which is driven in turn by a sprocket (not shown).

The stop lugs 107 are mounted on a cross bar 111 which in turn is secured to side blocks 112 (on each end) which are pivotally mounted on pins 114. The pins 114 are secured to the main frame. Two compression springs 115 (see Fig. 8), between flanges 116 depending from a transverse tie rod 117, and depending ears 113 of the side blocks 112 tend to pivot the stop lugs 107 upwardly at all times.

An upper paper feed roll 118, mounted horizontally, parallel to, and cooperating with the feed roll 105 is supported laterally by journals 120 which slide vertically in guides 121. The

guides 121 are silver soldered to the side blocks 112. The upper roll 118 does not touch the feed roll 105 when the side blocks 112 are pivoted upward so as to project the stop lugs 107 through the holes 106 in the lower plate 102, with the result that there is no compression on a sheet of paper stopped by the lugs 107 and the feed roll 105 merely rotates, sliding under the sheet. But when the stop lugs 107 are lowered to release the sheet, the upper feed roll 118 is lowered simultaneously, engages the sheet, and presses it against the feed roll 105. When this happens, the sheet is caught between the two feed rolls and propelled into the machine.

When the upper feed roll 118 engages the lower feed roll 105, the journals 120 slide up the guides 121 and compress a spring 124 held against the journals 120 by cross heads 125. This assures a relatively even feed roll pressure for different thicknesses of paper and renders fine adjustments unnecessary.

An arm 122 extends rearwardly from the left hand side block 112 and serves the purpose of pivoting the blocks 112 and their connected members. The arm 122 engages a cam 123 which is secured to the blanket cylinder 70, and depresses the arm 122 and blocks 112, once each cycle of the blanket cylinder. The cam 123 is cut and positioned to depress the arm 122 and cause the paper to be released while the blanket cylinder recess 71 is facing the pressure cylinder 90. More will be said presently about the precise timing of the cam 123 with respect to other cams and to the feeding and printing operations.

When the leading edge of the paper has passed between the cylinders 70 and 90 it is grabbed by gripper jaws which are similar to those described in my copending application Serial No. 755,065 and shown in that application in Fig. 5. As shown herein, referring to Fig. 10, they are supported on carriers 126 slidably mounted on shafts 127 connected to the inner face of the side plates 10 and 12, parallel to the said plates and slanting downwardly towards the rear. Each carrier 126 is reciprocated up and down its respective shafts 127 by lever arms 128 which are pivotally connected one to each side wall by pins 130 (see Fig. 9). The arms 128 connect to the carriers 126 by means of pins 131 which slide in appropriately formed slots in the upper end of the arms 128, during the stroke. The arms 128 are in turn reciprocated by action of links 132 connecting to slides 133 mounted in guides 134. The slides 133 are driven by side face cams 135 shown in dotted lines in Fig. 9.

The gripper jaws themselves comprise four jaw pieces 141 shown only in Fig. 10, evenly spaced along a cross bar 137 which passes horizontally across the machine and joins the two carriers 126. A shaft 138, mounted for rotation in the carriers 126 adjacent to and rearwardly from the cross bar 137, likewise passes across the machine between the carriers 126. The shaft 138 at each end mounts an arm 140 which serves to rotate the shaft 138 as will be explained. Along the shaft 138 the jaw pieces 141 are secured to the shaft 138. Each jaw piece 141 is provided with a spring 142 which presses against the cross bar 137 and tends to rotate the shaft 138, holding the lower jaws 141 in restrained relation against the forward edge 136 of the cross bar 137. The cross bar 137 is provided with slots 139 into which fits an upstanding flange 149 connected to the jaw pieces 141. The flange 149 serves as a stop for the leading edge of the paper.

The arms 140 serve the function of opening and closing the gripper jaws at the proper time and for this purpose each is provided with a pin 143 which is acted upon by fixed cams 144 and a rocker plate 145, there being but one rocker plate located on the inside of the side plate 10. At the end of the back stroke, the pins 143 ride up on the cams 144, causing the arms 140 to rise thereby pivoting the jaws open. Then as the carriers 126 start on the forward stroke, the arms 140 leave the cams 144, drop down and the jaws close momentarily but soon the pin 143 on the right hand arm 140 engages a flange 146 on the rocker plate 145 and commences to rise again. The rocker plate 145 is held with its rear edge tilted downward by a spring 147. Thus on the forward stroke, the pin 143 rides up on the flanges 146. Only one rocker plate is necessary because on the forward stroke, there is little tension or other cause for misalignment of the carriers 126. As the carriers 126 near the end of the forward stroke, the arm 140 will have been elevated and the jaws will be fully open. Also during the forward stroke, the rocker plate 145 tilts forward as the weight of the pin 143 passes the pivot point of the said rocker plate, and compresses the spring 147. Just before the end of the forward stroke, the pin 143 passes the forward end of the flange 146 and allows the arm 140 to drop and, consequently, the jaws to close. The jaws then remain closed until the end of the back stroke. It can readily be seen that this mechanism will not oppose a reversing movement of the rolls, a feature of importance when it becomes necessary to clean the rolls or for other reasons to reverse the rotation of the cylinders. Such a reversing action was not feasible with the mechanism of my copending application Serial No. 755,065, now U. S. Patent No. 2,590,179.

The paper is taken out of the gripper jaws at the bottom of the back stroke by a series of prongs or stripper fingers 148 which are supported by a cross bar 150. At this point, the paper passes downward onto a conveyor which first draws the leading edge of the paper rearwardly and then, when the paper is fully separated from the printing cylinders, conveys it into a pan in front of the machine by means of belts 151 (see Fig. 1). The apparatus for conveying the paper forward is fully described in my copending application above mentioned, and therefore, has been omitted here.

It is of importance, however, to prevent the leading edge of the paper from diving after it leaves the gripper jaws because if it does dive, it may enter the forward conveyor improperly and come out upside down. To take care of this, prongs 148 must be carefully designed. A straight slanting surface does not achieve the desired result, but rather it must be given a decided belly. If this is done, the leading edge is at first caused to buckle slightly and then in springing back, to follow around in conformance with the lower contours of the prongs 148.

The mechanism for holding the pressure cylinder 90 in the lowered position will now be described (see Fig. 4). It consists in two pawls 152 pivotally mounted on a shaft 153 which is in turn mounted in suitable journals secured to one of the main frame tie rods. The pawls 152 stand upright and are adjacent to the forward wall of each journal 91. The pawls 152 are provided with a hook shaped end which engages the above mentioned notch in the forward wall of each of the journals 91, the said notches being so located as to receive the pawls 152 when the

pressure cylinder 90 is in the lowered position whether depressed by the cams 75 or the cams 96. The pawls 152 thereafter hold the pressure cylinder 90 down until they are withdrawn from the notches. The pawls 152, being mounted on the shaft 153, swing in unison. They are controlled at the left side of the machine by a tension spring 154 and a solenoid 155. The tension spring 154 connects between a link 156 and the main frame. The link 156 is connected to the left hand pawl arm 152 and since the spring 154 tends to draw the link 156 rearwardly, it likewise swings the pawls 152 rearwardly holding them pressed against the journals 91 and ready to enter the notches when the said journals are lowered. The link 156 at its forward end is connected to a solenoid 155, which is controlled by a micro-switch 157. The solenoid 155 draws the link 156 forward against the tension of the spring 154, and in turn the pawls 152 are thereby swung forward. Since it is desirable to utilize the full stroke of the solenoid, a slot is provided in the link 156 to permit the full stroke to be taken without moving the pawl arms the entire distance. As shown in Fig. 4, the solenoid 155 is at the full extent of its forward stroke.

The solenoid 155 only acts to draw the pawls 152 forward when there is a sheet of paper present on the feed roll 105. The absence of a sheet is detected by a working arm 158 of the micro-switch 157. The working arms 158 is formed in the shape of a horse shoe, pivoted centrally and fitted with clearance into a circumferential groove 159 in the feed roll 105, its upper end lying in the path of the paper and its lower end controlling the micro-switch 157. In order to prevent the upper feed roll 118 from tripping the micro-switch 157, a similar and opposed groove 167 is likewise provided in the said upper roll 118. When a piece of paper enters between the feed rolls 105 and 118, the working arm 158 is depressed until its upper surface is flush with the top surface of the feed roll 105 in which position it trips the micro-switch 157.

The machine is driven by any suitable source of power turning a sprocket 160 located on the right hand side of the machine. Hand power can be used when the machine is not in operation to turn this sprocket when it is desired to rotate the cylinders small amounts forward or backward. The sprocket 160 serves to drive the feed and return belts by means of an endless belt 161. It also turns a shaft 162 upon which it is mounted, and drives an endless chain 163. The chain 163 serves to turn a shaft 164. The shafts 162 and 164 mounted in suitable bearings pass through the side plate 10 and driven pinions 165 and 166 respectively (see Fig. 9). The pinion 165 drives a gear 167 upon which the cam 135 is mounted. The gear 167 is mounted upon a shaft (not shown) which also serves to drive the endless chain 118 by means of a sprocket (not shown). Finally, the pinion 166, intermeshing with the gear 26, serves to rotate the plate cylinder 15, and thereby rotates the cylinders associated therewith as above described.

The operation of my invention will now be described paying particular attention to the positioning of the cams and their precise timing relationship to the various cylinders in the cycle of the machine. Let us start with the lithographic plate 30 already mounted on the cylinder 15, the moistening and ink rolls engaged, the blanket cylinder 80 in contact with the plate 30, the cylinder 90 held in the lowered position by the pawls

152, and with the power on. All of the cylinders will be rotating and the feed and return belts will be in motion. However, since no paper has as yet been introduced, the arm 158 of the micro-switch 157 will not have been depressed with the result that the solenoid 155 will not withdraw the pawls 152 and the pressure cylinder 90 will remain in the lowered position. Before introducing a sheet of paper let us examine the activity of the various cams. The cams 96 at each end of the blanket cylinder 70 will be rotating with each rotation of the blanket cylinder 70 and depressing the rings 98 of the pressure cylinder 90 each time the recess 71 passes the cylinder 90. But since the solenoid 155 is not being energized, the pressure cylinder 90 remains held in its lower position by the pawls 152. The cam 132 on the left end of the blanket cylinder 70 depresses the arm 122 once during each cycle and consequently the upper feed roll 118 and the stop lugs 107 are reciprocating up and down. Behind the pressure cylinder 90, the gripper jaws are also reciprocating, being driven by action of the cams 135. Once during each cycle, as the recess 71 commences to pass the cylinder 90, the gripper jaws come forward and enter the said recess momentarily at the top of their stroke, and then recede before the leading edge of the blanket 80 comes around.

Now let us introduce a sheet of paper. It is placed upon the belts 100 and carried between the plates 102 and 103, over the feed roll 105 and up against the stop lugs 107. The micro-switch 157 is tripped and the solenoid 155 draws the pawls 152 forward. It should be mentioned here that the upward compression of the springs 93 against the journals 91 is strong enough to prevent the solenoid 155 from withdrawing the pawls 152 when the cylinder is free. Thus the said pawls will not be withdrawn until the cams 96 come around and relieve this compression, even though a sheet of paper is present.

The cams 96 are located to depress the pressure cylinder 90 just after the trailing edge of the blanket 80 passes the pressure cylinder 90 in rotation. At this point the clear sheet will still be held in check by the stop lugs 107, but within a few degrees of rotation, the cam 123 depresses the arm 122 withdrawing the stop lugs 107 and lowering the upper feed roll 118. The sheet, now gripped between the two feed rolls is propelled into the machine. It will be noted at this time that the gripper jaws are entering the recess and there is space between the cylinders 90 and 70. The gripper jaws remain open until the last instant before the top of their stroke as above described, and the feed rolls propel the leading edge of the sheet into them while they are still open. For this latter purpose, the rotational velocity of the feed roll 105 must be carefully adjusted to assure entry of the leading edge of the sheet into the jaws but to avoid buckling of the paper. The cams 96 then allow the pressure cylinder 90 to rise, the pawls 152 having been withdrawn, the gripper jaws withdraw, and the sheet is pressed between the blanket 80 and the cylinder 90.

Thereafter, the sheet of paper passes on through, receiving the ink impression, the cam 123 allows the arm 122 to rise, disengaging the upper feed roll 118 and bringing up the stop lugs 107. If another sheet is not introduced, the cams 96 depress the cylinder 90 after the trailing edge of the blanket 80 passes, and since the solenoid 157 will not be energized, the pawls

152 will then enter the notches in the journals 91 holding the cylinder 90 in the lowered position.

If it is desired further to prevent the pawls 152 from disengaging the journals 91, the micro-switch working arm 158 can be adjusted not to respond to the weight of the paper but only to be depressed by virtue of the upper feed roll 113 pressing downward upon the paper to each side of the said working arm.

While numerous minor variations will be readily apparent to those skilled in the art, it is to be understood that the invention is not limited to the precise embodiment herein shown, but is rather to be measured by the scope of the following claims.

Having thus disclosed my invention and described in detail a preferred embodiment thereof, I claim as new and desire to secure by Letters Patent of the United States:

1. In a printing machine wherein a sheet of paper is pressed between two printing cylinders one of which carries a resilient blanket and serves the purpose of transposing an ink impression to the paper, the other having a smooth surface and serving the purpose of pressing the sheet against the blanket, means for feeding successive sheets of paper into the front of the machine, means for returning successive printed sheets to the front of the machine with printed sides uppermost, comprising carriers mounted for reciprocal movement in the direction toward and away from the rear of the printing cylinders gripper jaws mounted on the carrier for movement therewith and including means forming a part of the gripper jaws to render same effective to grip the leading edge of each sheet as it emerges from between the printing cylinders and leading it rearwardly and release the leading edge of the sheet near the end of the rearward stroke, fixed stripper fingers positioned alongside the grippers to engage the leading edge of the paper for removing same from the gripper jaws when open, a forwardly moving endless belt beneath the gripper jaws when in the rearward end of their stroke for conveying sheets deposited therefrom to the front of the machine, and means forming a part of the stripper fingers to buckle the paper upon engagement and guide same onto the belt.

2. A printing machine as described in claim 1 further characterized by stripper fingers having a profile contour as follows: first slanting rearward and downward, then bending around and presenting a forward slant while still continuing downward, and then bending back and finally slanting rearward and downward again, the said contour being so constructed and arranged as to dislodge the leading edge of a sheet from the gripper jaws, start it downward, buckle it slightly and then as it slips down, allow it to spring back thereby remaining in the horizontal position without being inverted.

3. A printing machine as described in claim 2 further characterized by springs holding the printing cylinders in pressure applying relation against each other, and the solenoid action not being sufficiently strong to withdraw the pawls unless the compression of the said springs against the said pawls is relieved by the said cams.

4. A printing machine wherein a sheet of paper is pressed between two rotating cylinders, one of which transposes ink to the paper, having in combination means for separating the cylinders momentarily once during each cycle of the ma-

chine, and a feeding mechanism carrying successive sheets of paper from the front of the machine to the bite between the cylinders, comprising the following members, viz, belts conveying the sheet, stops arresting the progress of the sheet at a point adjacent to the bite between the cylinders, a lower feed roll mounted for axial rotation in fixed bearing adjacent to the said stops, the said lower feed roll supporting the sheet when the latter is arrested by the stops, an upper feed roll mounted for movement towards the lower feed roll and mounted in bearings for free rotation, a pivotally mounted frame supporting both the stops and the upper feed roll, and a cam operatively associated with the printing cylinder for simultaneously causing the said stops to be released and the said upper feed roll to press the sheet against the lower feed roll for feeding the sheet into the space between the printing cylinders, means for guiding successive sheets rearwardly after the printing operation, comprising gripper jaws mounted for reciprocation from the rear of the machine into the space between the printing cylinders when they are separated, a cam for opening the jaws at the rear end of their travel and closing them at the forward end, means for rotating the lower feed roll at such a velocity as to place the leading edge of the sheet in the gripper jaws before the gripper jaws close and commence their rearward motion, means for stripping the sheet from the gripping jaws after they have completed their rearward stroke, and belts conveying the sheet to the front of the machine.

5. In a printing machine wherein a sheet of paper is pressed between two printing cylinders one of which carries resilient blanket and serves the purpose of transposing an ink impression to the paper, and the other cylinder has a smooth surface and serves the purpose of pressing the sheet against the blanket, cams separating the cylinders momentarily once during each cycle of operation, and mechanism for feeding the sheet into the bite between cylinders, guiding it at first rearwardly and then guiding it to the front of the machine, comprising a lower feed roll for guiding the paper up to the bite between the cylinders, stops arresting the progress of each sheet as it reaches a position adjacent to said bite, an upper feed roll operatively associated with the lower feed roll, a cam for simultaneously withdrawing said stops and lowering the upper feed roll to press the sheet against the lower feed roll at a time when the two printing cylinders are in separated position, reciprocable gripper jaws movable linearly forwardly and back to enter the space between the cylinders when they are separated, means for opening the gripper jaws to receive the leading edge of the sheet at the forward end portion of the stroke to grip the paper and lead same rearwardly, means to open the jaws near the rearward end of their stroke to release the sheet, a forwardly moving endless belt located below the gripper jaws when in the rearward end of their stroke to relay the released sheet to the front of the machine, guides for removing the sheet when released from the gripper jaws and guiding same onto the belt for delivery onto the front of the machine, means for rotating the lower feed roll to cause the sheet to advance into the space between the two cylinders sufficiently for the leading edge of the sheet to lodge into the gripper jaws and which is further characterized by pawls holding the printing cylinders apart after they have been separated, means for releasing the said pawls to allow the

cylinders to press a sheet of paper between them, comprising a micro-switch, a pivotally mounted horseshoe shaped working arm for the said upper and lower feed rolls, the said working arm being so constructed and arranged as to fit into the groove of the lower feed roll with its upper end extending into the groove of the upper feed roll when the upper feed roll is lowered without a sheet of paper between the two feed rolls, but to be depressed by the weight of the sheet and 10 the action of the upper feed roll when a sheet of paper is present closing the said micro-switch, and a solenoid controlled by the said micro-switch withdrawing the said pawls.
